ABSTRACT: A combination flasher buzzer relay device having switch means operated by either of two coils, one in parallel with a condenser as a time constant control to operate the device as a flasher and the other to operate it as a buzzer.

FLASHER BUZZER DEVICE

SUMMARY OF THE INVENTION

This invention relates to a flasher buzzer device for automotive use.

Present day automobiles provide for a turn signal flasher device embodying a relay. Separately, a buzzer device may be provided at substantial extra cost to warn the driver of inadvertence such as ignition circuit on, headlights on, or the like.

The invention has for its main object the provision of a relay device adapted to serve the dual functions of a flasher unit and a buzzer or inadvertence signal unit.

BRIEF DESCRIPTION OF THE DRAWING

The FIGURE of the drawing shows an electrical schematic of the preferred mode.

DESCRIPTION OF THE EMBODIMENTS

The relay 10 embodies a core 11 having winding 12, 12a thereon which when energized closes normally open contacts 13, 14, the armature contact 14 being normally closed with contact 15.

The flasher circuit for left and right hand turn signal lamps 16, 17 embodies the turn signal switch 18 connecting to normally open contact 13 and winding 12a at 19, the winding being connected in parallel from terminal 19 with condenser 20 to terminal 21 and through voltage dividing resistor 22 to line 23 connecting positive terminal 24 to armature contact 14.

In flasher circuit operation, closure of turn signal switch 18 with either of turn lamp circuits 16 or 17 energizes winding 12a closing contacts 13, 14 completing the lamp circuit for a

time period determined by the time constant of the condenser 20 and winding 12a. Preferably, resistor 22 is of the same resistance as that of winding 12a.

In the buzzer mode of operation normally closed contact 15 connects winding 12 through a control switch 25 by terminal 26 to ground. The buzzer control switch 25 may be actuated by conditions such as an open door, a key in the ignition in the ON position, or like circumstances of operator inadvertence. Closure of switch 25 energizes winding 12 effecting closure of contacts 13, 14 short-circuiting directly to terminal 23 releasing armature contact 14 to engage contact 15 to continue a buzzing action.

A single relay having a normally open and a normally closed set of contacts including a common armature with two relay windings thus serves the utility described wherein several separate buzzer control switches 25 connecting to terminal 26 may serve several separate warning requirements. In such instances a pilot lamp 27 may be connected in each separate buzzer warning circuit having its own control switch 25; but a single buzzer device only is employed.

We claim:

1. A flasher buzzer device comprising a relay having a first winding and a second winding, a movable contact, and a first fixed contact and a second fixed contact, one end of the second winding connected to the first fixed contact and the other end connected to a control switch, a source of electricity connected to one end of the first winding and the other end connected to a multiple light switch connected to ground through a light source, the other end of the first winding is also connected to the second fixed contact and the source of electricity is connected to the movable contact.
